UNITED STATES PATENT OFFICE.

ROBERT J. TURNBULL AND GEORGE G. LYNCH, OF WILMINGTON, NORTH CAROLINA.

METHOD OF MAKING LOUVERS.

Original application filed July 27, 1925, Serial No. 46,457. Divided and this application filed December 31, 1925. Serial No. 78,656.

This invention relates to ventilators, and more particularly to a method of manufacturing ventilator louvers, and is a division of our application Serial No. 46,457, filed July 27, 1925. The invention has for its object to provide a cheap and expeditious method whereby louvers of great strength and efficiency may be manufactured at a minimum cost.

With these objects in view, the invention consists in forming the body of the louver at a single operation and simultaneously providing said body with an opening whereby means for connecting the louver to an operating rod may be expeditiously and efficiently secured thereto, and also in the same operation, so shaping the louver as to enable the pivoting means for the louver to be quickly and securely fixed thereto, preferably by spot welding.

For the purpose of facilitating the description of the invention, reference is made to the accompanying drawings, in which,—

Fig. 1 illustrates a rectangular piece of sheet metal, such as sheet iron, sheet steel or sheet copper;

Fig. 2 is a perspective view of the sheet shown in Fig. 1 after the same has been shaped as by a single operation;

Fig. 3 illustrates one form of the louver complete, with the pivot means and the device for connecting the same to the operating rod;

Fig. 4 is a section on the line 4—4 of Fig. 3; and

Fig. 5 is a section on the line 5—5 of Fig. 3.

In said drawings, like reference numerals indicate like parts throughout the several views. In practicing the invention, we take a sheet 6 of any suitable metal, as sheet iron, sheet steel, sheet copper, of the length of the desired louver and of a suitable width, and each louver is then stamped or otherwise formed from said metal stock in a suitable machine by a single operation, as for example in a stamping machine, so as to produce a substantially wide medial portion 7, and reversely bent narrower front and rear flange portions 8 and 9. At the same time the bending on the line of flange portion 9 is intended to receive the pivot means for the louvers, and a hole 10 (Fig. 2) is punched centrally of the louver in the medial portion 7 and adjacent the bending line of flange 8.

The indentations 11 may be of any desired length, even to the extent of the entire length of the bending line of the flange 9, without departing from the spirit of the invention, and the pivot may be separate pins 12, 12, 80 as shown, or in any other form, and located in the indentations and secured therein by spot welding or otherwise. Each louver is then provided with a suitable means for connecting the louver to an operating rod, which means is here shown in the form of a clevis 13, preferably U-shaped in cross-section and secured to the louver by a rivet 14 which passes through the bottom of the clevis and through the opening 10. The louver and the 70 clevis are then further secured together at the sides of the clevis by spot welding as indicated at 15, 15 (Fig. 4), whereby the clevis is prevented from turning on the pivot and working loose. 75

By manufacturing the louver in accordance with the method described, a louver of great strength and simplicity of construction is secured, while the materials employed and the steps necessary in the manufacture 80 thereof enable us to produce a louver of superior quality and at minimum cost.

What is claimed is:—

1. The method of making ventilator louvers which comprises reversely bending opposite edge portions of a piece of metal stock to form flanges defining a medial portion and simultaneously indenting the bending line of one of the flanges, and then securing pivot means along said indented 85 bending line.

2. The method of making ventilator louvers, which comprises reversely bending opposite edge portions of a piece of metal stock to form flanges defining a medial portion and simultaneously indenting the bending line of one of the flanges and punching a 95 clevis-attaching opening centrally of the article adjacent the bending line of the other flange. 100

3. The method of making ventilator louvers which comprises reversely bending opposed edges of a piece of metal stock to provide a medial portion and a pair of flanges and simultaneously indenting each 105 end of the article on the bending line of one of the flanges to form a pair of pivot pin depressions, securing a pair of pivot pins in said depressions by welding, and forming a clevis-attaching opening centrally of 110

said medial portion and near the bending line of the other flange.

4. The method of making ventilator louvers which comprises reversely bending opposed edges of a piece of metal stock to form flanges defining a medial portion wider than the flanges and simultaneously indenting the ends of the article on the bending line of one of the flanges to form a pair of pivot pin depressions and forming a clevis attaching opening in said medial portion adjacent the bending line of the other flange, and securing a pair of pivot pins in said depressions by spot welding.
5. The method of making ventilator louvers, which comprises reversely bending the edges of an elongated piece of metal stock to provide flanges thereon and simultaneously indenting each end of the article

on the bending line of one of the flanges to 20 form pivot pin receiving depressions and punching a hole centrally of the article adjacent the bending line of the other flange, whereby a clevis may be secured to the louver.

6. The method of making ventilator louvers, which comprises reversely bending the edges of an elongated piece of metal stock to provide flanges thereon and simultaneously indenting each end of the article on the bending line of one of the flanges to form pivot pin depressions, and then securing pivot pins in said depressions by spot welding.

In testimony whereof we have signed this specification.

ROBERT J. TURNBULL.
GEORGE G. LYNCH.
